UNITED STATES PATENT OFFICE

111,029

DESIGN FOR AN INSULATED RECEPTACLE FOR FOOD OR LIQUID

John R. Morgan, Oak Park, Ill., assignor to Sears,
Roebuck and Co., Chicago, Ill., a corporation
of New York

Application January 27, 1938, Serial No. 74,587

Term of patent 7 years

To all whom it may concern:

Be it known that I, John R. Morgan, a citizen of the Republic of Guatemala, residing at Oak Park, in the county of Cook and State of Illinois, have invented a new, original, and ornamental Design for an Insulated Receptacle for Food or Liquid, of which the following is a specification, reference being had to the accompanying drawing, forming a part thereof.

Fig. 1 is a perspective view of an insulated re-

ceptacle for food or liquid embodying my new design.

Fig. 2 is an elevational view of the same, with bail in lowered position.

The side not seen in the drawing is substantially similar in appearance to the side shown.

I claim:

The ornamental design for an insulated receptacle for food or liquid, as shown and described.

JOHN R. MORGAN.
